UNITED STATES PATENT OFFICE

154,262

DESIGN FOR A NEGLIGEE

Violet Giovagnoni, New York, N. Y.

Application October 30, 1948, Serial No. 149,408

Term of patent 7 years

(Cl. D3—26)

To all whom it may concern:

Be it known that I, Violet Giovagnoni, a citizen of the United States, residing in New York city, in the county of New York and State of New York, have invented a new, original, and ornamental Design for a Negligee of which the following is a specification, reference being had to the accompanying drawing, forming part thereof.

Fig. 1 is a front view of a negligee, showing my design, and

Fig. 2 is the rear view thereof, on a reduced scale.

I claim:

The ornamental design for a negligee, substantially as shown.

VIOLET GIOVAGNONI.
